 (Continued)*Primary Examiner* — Cynthia R Underwood*(74) Attorney, Agent, or Firm* — Cristian Andres Rodriguez(57) **CLAIM**

The ornamental design for a side-opening curved cord trough as shown and described.

DESCRIPTION

FIG. 1 is a perspective view of a side-opening curved cord trough showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a perspective view of a side-opening curved cord trough showing my new design, in a closed state.

The broken lines depict portions of the side-opening curved cord trough and form no part of the claimed design.

The side-opening curved cord trough is shown with a symbolic break in its length. The appearance of any portion of the article between the break lines forms no part of the claimed design.
